UNITED STATES PATENT OFFICE.

BURTON R. PETERS, OF ERIE, PENNSYLVANIA.

SCAFFOLD.

1,147,541.

Specification of Letters Patent.

Patented July 20, 1915.

Application filed May 25, 1912. Serial No. 699,682.

To all whom it may concern:

Be it known that I, BURTON R. PETERS, a citizen of the United States, residing at Erie, in the county of Erie and State of Pennsylvania, have invented new and useful Improvements in Scaffolds, of which the following is a specification.

The general object of the invention is to facilitate the erection of scaffolds, such as are used in connection with the erection of buildings, and the adjusting of the platforms thereof to various distances above the ground as the height of the walls of the building is increased.

Other objects will appear and be better understood from the following description taken in connection with the accompanying drawings, in which,

Figure 1 is a perspective of an embodiment of the invention surrounding a building. Fig. 2 is an enlarged detail perspective of one of the uprights, contracted, and also showing the means for adjusting the floor supports. Fig. 3 is a fragmentary perspective of the brace rods and one of the uprights. Fig. 4 is a detail perspective of the brace rod coupler also showing fragments of brace rods connected thereto.

The device is chiefly intended for use in building construction, although it may be used in connection with any work in which a scaffold is required. When erected or set up, the device, herein designated generally by *a*, surrounds the building *b* so that the workmen on the various platforms herein-after described, may have access to the various walls of the building.

c indicates the uprights or post supports. The number employed of these elements will be governed both by the character of the building and the work. These uprights may be of any desired construction, and in the embodiment shown, they are skeleton structures and preferably rectangular in cross section.

5 indicates the metallic rods or legs of each upright, and *6* the cross pieces or rounds connecting said legs. The frames *4* are removably secured to the upper ends of the uprights in order to admit of extending the lengths of the uprights, which is preferably done by telescoping uprights of smaller area into the upper ends of lower ones after the frames

have been removed, and securing the uprights together by bolts, all of which will be obvious to those skilled in the art.

d indicates connecting or tie rods of any desired construction and material, and arranged end to end. Their function is to brace the uprights, and they are preferably, though not necessarily formed of metal tubing and rendered extensible by telescoping the sections *10* into larger sections *7*. This structure admits of varying the area of the device, within certain limits, without changing the rods, and the clamping collars *11* which are adjustably secured to the smaller sections *10*, serve, by abutting the ends of the larger sections, to prevent the smaller from moving into the larger sections after the device is set up.

8 indicates the double ended sockets which connect the adjacent ends of the rods *d*. These sockets are preferably cast with a plurality (preferably four) of obliquely disposed openings in their opposite ends which receive the adjacent ends of the tubes *7*. As shown in Fig. 3 the oblique sockets *9*, which receive the outer ends of the rods *d*, are preferably formed with the uprights.

From the foregoing it will have been observed that the braces or trusses diverge from the sockets *8*, whereby, to flank a relatively large area on the uprights *c*.

The adjustable platform supports are designated generally by *e*. In use, the number employed of these supports will invariably be governed by the height and character of the structure which the device is used in connection with. As shown in Figs. 1 and 2, each platform support may include two cars or trucks made up of shafts *12* journaled in flanged wheels *13*, which bear on angular treads *14*, on the verticals *5* and have their corresponding ends connected by cables *15* which form supports for the tread boards *26*, shown in Fig. 6, and which are drawn taut, by turning the shafts by means of the crank handles *16*; return movement of the shafts being prevented by pawls *19*, carried by plates *17*, which slide on the verticals *5*, and in which the shafts *12* have bearings, and ratchet wheels *20* secured to the shafts *12*.

As shown, the structure is provided with upper and lower platform supports which

may be raised or lowered either independently or simultaneously. For purposes of illustration, I have shown an arrangement for raising and lowering the said platform 5 supports simultaneously, although the structure is shown as associated with Figs. 1 and 2 only. 21 indicates sheaves in the upper frames 4, and 22—22 indicate drum shafts on remote faces of adjacent uprights and at the 10 lower end portions thereof. 23, 23 indicate cables trained over the sheaves 21 and connected at one end to the drum shafts 22 and also connected by clamps 23' to the shafts 12 of the upper and lower cars or trucks, or 15 the shafts 27—28 as the case may be. With this construction it will have been observed that when drum shafts on adjacent uprights are turned so as to wind the cables thereon, the upper and lower cars on the said uprights will be raised. In this connection it 20 will have been observed also that the truck shafts do not turn but the wheels 13 move on the tracks 14, thus carrying bodily upward, the cables connected to the shafts and 25 the parts carried by the cables.

A convenient method of arranging sub-scaffolds is shown in Fig. 1, wherein it will be observed that cables or wires 25 extend through the building so as to admit of arranging a scaffold for the operators on the 30 interior of the building. These wires 25 have their opposite ends suitably secured such as by clamps 26, to the wires or cables 25 35 so that when the wires 15 to which they are connected are raised and lowered, the said wires 25 will also move. With this arrangement as many sub-scaffolds as desired,

and within the limits of the device, may be connected to the wires 15.

What I claim as new is:

1. In adjustable scaffolding, the combination with a plurality of uprights, braces connecting the uprights, flexible elements extending between the uprights, means carried by the uprights for tensioning said 45 flexible elements, a shaft on which the flexible element is wound, means for rotating the shaft to tension the element, wheels mounted upon said shaft and adapted to travel longitudinally of the upright, and 50 manually operable means carried by the upright and connected to said shaft for moving the latter longitudinally of the upright.

2. In an adjustable scaffold, the combination with a plurality of uprights, braces connecting the uprights, flexible elements extending between the uprights, shafts on the uprights and upon which the flexible elements are wound, wheels mounted upon the 55 shafts and adapted to travel longitudinally 60 of the uprights, means for rotating the shafts for tensioning the flexible elements, and means for holding the shafts against rotation when the flexible elements are placed under tension, and means carried by 65 the uprights and connected to the shafts for moving the latter longitudinally of the uprights.

In testimony whereof I affix my signature in presence of two witnesses.

BURTON R. PETERS.
